Patented Dec. 16, 1924.

UNITED STATES PATENT OFFICE.

EDWARD MEAD JOHNSON, JR., OF EVANSVILLE, INDIANA.

PROCESS OF PRODUCING COD-LIVER OIL.

No Drawing.

Application filed June 14, 1924. Serial No. 720,125.

To all whom it may concern:

Be it known that I, EDWARD MEAD JOHNSON, Jr., a citizen of the United States, residing at Evansville, in the county of Vanderburgh and State of Indiana, have invented certain new and useful Improvements in Processes of Producing Cod-Liver Oil, of which the following is a specification.

This invention relates to a process of producing oils from fish livers, and more particularly to a process of producing cod liver oil.

My improved process consists in rendering cod liver oil directly from livers, without the use of heat, such oil being free from stearine.

Heretofore the process of rendering oil from livers consisted in applying heat, either by direct steam or hot water, or steam jacketed kettle. The heat disintegrates the connective tissue of the livers and causes the cells to burst open and give up their oil. When oil is rendered by such a process, from twenty to thirty per cent of stearine comes over with the oil, depending upon the length of time during which heat is applied.

In order to use cod liver oil so rendered for medicinal purposes, it has been customary to remove the stearine by another and separate procedure. The removal of the stearine has been accomplished by freezing the previously rendered oil at 15 to 18° F. whereupon the stearine in the oil congeals. This stearine is then removed by placing the frozen oil in fine mesh calico or muslin bags. The oil drips from these bags and the stearine remains behind, provided the freezing temperature is maintained. Such oil, with the stearine removed, is marketed as refined, non-freezing, medicinal oil.

By my improved process, the refined, non-freezing medicinal oil can be produced directly from the livers, and is initially free from stearine.

This I accomplish by subjecting the fresh livers to a temperature several degrees below the freezing point and maintaining the livers in a frozen condition until the oil is pressed therefrom.

By this method, the water in the livers is turned into ice, the ice crystals breaking up the cellular structure of the livers being treated and putting them in condition so that when pressure is applied, the oil can readily flow out. The freezing also has the effect of solidifying the stearine so that

when the oil is pressed out of the livers, the stearine is retained in the solid mass and does not enter into the oil at all.

In practice, I prefer to use a jacketed, glass-lined tank wherein the livers are placed, a freezing compound or brine being pumped through the surrounding jacket to freeze the livers. When sufficiently frozen, the livers are removed from the tank and maintained in frozen condition by being placed in suitable containers, preferably linen bags, suspended from rods in a room kept at a temperature below freezing. This below freezing temperature may be readily maintained by circulating a suitable freezing compound through conduits or pipes laid in the room.

The next step is to subject the livers to pressure in any suitable press whereby the oil will flow out. The extraction of the oil from the livers may be facilitated if desired, by reducing the livers to small particles by grinding or otherwise, before the pressing step.

It is essential that the livers be maintained in frozen condition throughout the process, so that no emulsion will be formed in the finished product. It may be desirable to use, also, in connection with the press, a fabric or other filtering medium to retain solid particles while permitting only pure, clear oil to flow therethrough.

My improved method not only produces a relatively large quantity of oil as compared to the quantity of liver treated, but has the effect of retaining in the solid mass and keeping out of the oil initially all of the solid fats or stearine, thereby producing an oil characterized by a lack of smell and taste, and having a desirable light color.

If any small quantity of recoverable oil be left in the mass of solids retained in the press or filter after practicing my invention, the same may be recovered by any of the well known methods, such as boiling out the pressed residue with water. In such case the oil will separate and come to the surface and may be removed. It will be understood that this oil is not clear of stearine and must be reduced in temperature in order to permit the stearine to be removed.

I claim as my invention:

1. The process of producing cod liver oil which consists in freezing cod livers and in pressing the livers while in a frozen condition to extract the oil therefrom.

2

2. The process of producing cod liver oil which consists in freezing the liver sufficiently to form ice crystals therein and rupture the cellular structure thereof, maintaining the liver in frozen condition and pressing the oil therefrom.

3. The process of producing cod liver oil which consists in freezing the liver sufficiently to form ice crystals therein and rupture the cellular structure thereof, maintaining the liver in frozen condition, reducing the

liver to small particles and then pressing the oil therefrom.

In testimony, that I claim the foregoing as my invention I affix my signature, in the presence of two witnesses, this 10th day of June, 1924.

EDWARD MEAD JOHNSON, JR.
